DESIGN FOR AN EYELASH CURLER CONTAINER

William R. Tuttle and William J. Beldue, Rochester, N. Y., assignors to The Kurlash Company, Inc., Rochester, N. Y., a corporation of New York

Application September 4, 1948, Serial No. 148,468

Term of patent 14 years

(Cl. D86—10)

To all whom it may concern:

Be it known that we, William R. Tuttle and William J. Beldue, citizens of the United States of America, and residents of Rochester, county of Monroe, State of New York, have invented a new, original, and ornamental Design for an Eyelash Curler Container, of which the following is a specification, reference being had to the accompanying drawing, forming part thereof.

Fig. 1 is a front elevation of an eyelash curler container, showing our new design;

Fig. 2 is a side elevational view of the same, showing the cover flap in partly raised position;

Fig. 3 is a rear view of the container, and

Fig. 4 is a top plan view of the same.

We claim:

The ornamental design for an eyelash curler container, substantially as shown.

WILLIAM R. TUTTLE.
WILLIAM J. BELDUE.
